(57) **CLAIM**

The ornamental design for a millimeter-wave radio equipment enclosure, as shown and described herein.

DESCRIPTION

FIG. 1 is a left side, front, and top perspective top view of a millimeter-wave radio equipment enclosure, showing the new design;

FIG. 2 is a front elevational view thereof;

FIG. 3 is a top plan view thereof;

FIG. 4 is a left side elevational view thereof;

FIG. 5 is a right side elevational view thereof; and,

FIG. 6 is a bottom plan view thereof.

The broken lines showing a support post and other enclosures in FIG. 1 depict environmental structure that forms no part of the claimed design.
